WILHELM BRÜGMANN, OF DORTMUND, GERMANY.

APPARATUS FOR TIPPING FOUNDRY-LADLES.

No. 896,054.

Specification of Letters Patent.

Patented Aug. 11, 1908.

Application filed March 6, 1908. Serial No. 419,534.

To all whom it may concern:

Be it known that I, WILHELM BRÜGMANN, a subject of the King of Prussia, residing at 23 Bornstrasse, Dortmund, Germany, have 5 invented certain new and useful Improvements in Apparatus for Tipping Foundry-Ladles; and I do hereby declare the following to be a full, clear, and exact description of the invention.

10 This invention consists in an improved apparatus for tipping foundry ladles by means of which the ladle can be lifted off its carriage and tipped in one movement, so that the liquid metal can be poured out with the 15 greatest possible uniformity.

The apparatus consists substantially of 20 two rotary disks or wheels arranged independently of the ladle, between which the ladle supported on its carriage is introduced 25 and by which it is engaged in such a manner that by rotating the said wheels the ladle will be lifted off its carriage and tipped.

The connection between the ladle and the 25 wheels may be effected by providing the latter with open bearings adapted to receive pins arranged on the sides of the upper part of the ladle, and also with an arm, preferably constructed as a connecting bar, adapted to come against the lower part of the front of 30 the ladle.

By the rotation of the wheels the ladle is first lifted off its carriage by means of the bearings engaging with its upper side pins, and then, as the arm on the wheels comes 35 against the front of the ladle, the ladle is tipped thereby. The arrangement is preferably such that the spout of the ladle in tipping, will be situated in the axis of rotation of the two wheels.

40 In the accompanying drawings, Figure 1 is a side elevation, Fig. 2 a front elevation, and Fig. 3 a plan, of one form of the improved tipping apparatus.

The ladle, *a*, is supported by its two trunnions, *c*, on the brackets, *d*, of the carriage, *b*. The ladle is fitted at its upper edge with a strengthening ring *q*, provided with pins, *r*, situated over the trunnions, *c*.

Suitable standards, *e*, support in bearings, 50 *f*, the axles of two wheels or disks, *g*, which are arranged at a distance apart sufficient to allow the carriage *b*, with the ladle, *a*, to be run in between them, as shown in Fig. 2. On the inner sides of the wheels, *g*, 55 there are provided open bearings, *k*, adapted to receive the upper pins, *r*, of the ladle.

The two wheels are connected together by a bar, *n*, which is adapted to be brought by the rotation of the wheels against the front of the lower part of the ladle. The two 60 wheels are also connected together on the opposite side by means of one or more struts or bracing rods or bars, *m*, so that the two wheels are compelled to rotate as a single entity. The rotary movement of the wheels, *g*, is 65 produced by means of two toothed wheels, *p*, mounted on a shaft, *o*, and engaging each in a toothed arc extending from a point, *h*, to a point, *i*, around the periphery of each wheel, *g*. Counterweights, *l*, are provided for the 70 purpose of facilitating the tipping of the ladle.

The operation of the apparatus is as follows:—The carriage, *b*, with the ladle, *a*, is run from the left (Fig. 1) between the two 75 wheels, *g*, which have been rotated slightly towards the left from the position shown in Fig. 1, so as to bring the bearings *k* below the pins, *r*, and out of the way of the carriage. Suitable stops are provided to hold the carriage with the ladle in the correct position. When this has been accomplished, the shaft, *o*, is rotated by suitable means so as to rotate the wheels, *g*, in the direction indicated by the arrow in Fig. 1. In this manner, the 80 bearings, *k*, are moved up against the pins, *r*, on the ladle so as to lift the ladle off the supports, *d*. Then by the continued rotation of the wheels, *g*, the bar, *n*, is brought to bear against the front of the lower part of the ladle 85 and the latter is thereby caused to turn on the axis of the wheels, *g*, and thus be tipped. The bearings, *k*, and the bar, *n*, are preferably so arranged that the spout of the ladle, when tipped, will be situated in the axis of 90 rotation of the wheels. When empty, the ladle is turned back into its trunnion bearings on the standards, *d*, of the carriage *b*.

Having now particularly described and ascertained the nature of my said invention, 100 and in what manner the same is to be performed I declare that what I claim is:—

1. An apparatus for tipping foundry ladles, comprising a pair of suitably supported rotary members adapted to be actuated in 105 unison, means for engaging a ladle between the same, and means in connection with the rotation of said members for lifting said ladle from its support and tipping the same, in combination with a movable support adapted to convey said ladle to the tipping apparatus, substantially as described.

2. An apparatus for tipping foundry ladles, comprising a pair of suitably supported rotary members adapted to be actuated in unison and provided with open bearings to receive bearing pins on opposite sides of a ladle and with a transverse bar extending between said members and adapted to impinge against the side of said ladle on the rotation of said members, in combination with means to rotate the latter, substantially as described.

3. An apparatus for tipping foundry ladles, comprising a pair of suitably supported rotary members adapted to be actuated in unison and provided with open bearings to receive bearing pins on opposite sides of a ladle and with a transverse bar extending between said members and adapted to impinge against the side of said ladle on the rotation of said members, in combination with a ladle having side bearing pins and a spout, said bearing pins, transverse bar and open bearings being so arranged with relation to one another that on rotation of said members the spout is located during the tipping operation substantially on the axis of rotation of said members.

4. An apparatus for tipping foundry ladles, comprising a pair of suitably supported

rotary members provided with counter- 30 weights and adapted to actuate in unison, open bearings carried thereby to receive bearing pins on opposite sides of a ladle, a transverse bar extending between said members and adapted to impinge against the side 35 of said ladle on the rotation of said members, in combination with means to rotate the latter, substantially as described.

5. An apparatus for tipping foundry ladles, comprising a pair of suitably supported 40 rotary members adapted to be actuated in unison and provided with open bearings to receive bearing pins on opposite sides of a ladle and with a transverse bar extending between said members and adapted to impinge 45 against the side of said ladle on the rotation of said members, in combination with a segmental rack on each of said rotary members, gear wheels intermeshing therewith and means for rotating the latter, substantially 50 as described.

In testimony whereof I have signed my name to this specification, in the presence of two subscribing witnesses.
